UNITED STATES PATENT OFFICE

GEORGE LOCKE CROSBY, OF EAST ORANGE, NEW JERSEY

LOOSE LEAF BINDER

Application filed December 14, 1929. Serial No. 413,956.

This invention relates to loose leaf binders of the ring type wherein individual sheets, pamphlets, bulletins and the like may be conveniently inserted and removed. It is particularly well adapted for use in the binding of sheets, catalogs, bulletins, illustrations, drawings and forms of many kinds where, from time to time, such additional matter is issued and where former inserts are replaced, superseded, or supplemented. It enables one to conveniently keep his binder up-to-date.

One of the main objects of the invention is to provide a very simple and inexpensive form of binder, the cost of which may be so low that it enables one to distribute the same generally without incurring a burdensome expense. Another object is to provide a form of construction which can be readily and economically made to suit any required size of inserts and any number of inserts. Another object is to not only produce a form of binder which is universally applicable to various uses but to produce one of attractive appearance with a smooth outside back- ing which adequately protects the bound material and enables the same to have a distinctive appearance when in place on a shelf so as to be readily distinguished from other books. Another object is to produce an im- proved form of structure which will have all the advantages of more expensive forms of binders as regards ease of removal and insertion of individual inserts. Another object is to permit the use or non-use of a cover, as may be desired, and to permit the use of a cover of any desired material or thickness. Another object is to secure a durable form of construction and one which will permanently retain its attractive appearance. Other objects and advantages will be understood from the following description and accompanying drawings.

Fig. 1 is a front inside elevation with the cover in place and open and partly broken away; Fig. 2 is a side view with the cover partly broken away; Fig. 3 is an end view; Fig. 4 is a plan view showing the binder in development and without the rings; Fig. 5 is an end view of a modified form with the rings and cover in place; Fig. 6 is an end

view of the ring holders of the form shown in Fig. 5; Fig. 7 is an end view of the clips of the form shown in Fig. 5; and Fig. 8 is an elevation of the form shown in Fig. 5, looking between the sides of the cover.

Referring to Figs. 1 to 4, the binder comprises a main element 1, which forms the back plate and is made of the proper length and width to accommodate the inserts to be bound. It forms an external back protecting and supporting element. It is conveniently made of metal such as aluminum, brass, tin and the like and may be plated or finished in any way desired to have an attractive appearance. It is conveniently stamped out of sheet metal of the form shown in Fig. 4 having a series of projections, clips or lips 1a, extending from the sides and also a series of oppositely disposed projections or ears 1b extending from the sides. The projections 1b have perforations 1c for receiving the usual openable and closable rings 2. The ends of the main binding element 1 may be slightly rounded, if desired, as shown in the drawings, and this element may also be bent to have an exterior convex form along its length, as indicated in Figs. 1, 2 and 3 to give it more rigidity and to enhance its appearance, although this element may be flat if desired.

In assembling the parts, the projections 1a and 1b are first bent inwardly at approximately right-angles to the main element and then the cover 3 is pushed against the projections so that they pass through the cover at its mid-portion. The projections or lips 1a are then bent inwardly against the cover and the main element 1 so as to hold the cover firmly in place against the main element 1. The ears 1b are also bent inwardly at an angle of about 45°, as well shown in Fig. 3. The rings 2 are then slipped through the perforations 1c and the sides of the cover 3 are then bent inwardly, completing the binder, as shown in Fig. 3. The rings 2 may be of any openable form which has a hinge or joint at one portion and which is adapted to open at a point diametrically opposite the hinge or joint. These rings of various forms are available on the market in many different

sizes and may be purchased in quantities at low cost and of a size to suit the particular requirements.

It is evident that this form of construction is readily adaptable for any size of binder as regards length or thickness by merely making the main element 1 of the required length and width. It will likewise be understood that any desired number of clamping lips 1a may be provided to insure the holding of the cover permanently in position; and likewise any desired number of the ears 1d may be provided for the receipt of any number of rings 2. It is also evident that the cover 15 may be of any ordinary thickness and of any material without modification of the element 1 or of the projections 1a and 1b. If the cover be of such thickness or character that it cannot be easily pierced by the projections 1a and 1b, the cover may be cut to form slots in the proper locations to receive these projections when uniting the cover with the main supporting element. It is also evident that this form of construction permits the use of a cover having the same thickness throughout and does not require any reinforcement or additional layers of material at the back. If desired, the binder may be used without the cover, in which case the 30 projections 1a become unnecessary; but for the most purposes, such as catalogs or bulletins, a decorative cover is used of a character to protect the bulletins or catalogs and this cover, as already explained, is clamped in 35 place to the main element 1, while permitting the convenient insertion and removal of individual sheets or pamphlets by means of the rings 2.

Instead of using bendable material for the main element 1, this element may be made of any stiff unbendable material such as celluloid, fiber and the like, in which case the construction shown in Figs. 5 to 7 may be utilized. Here this main element is indicated as a flat plate or strip 4 and is not provided with the integral projections 1a or 1b. Instead of the projections, 1a, a bendable metal clip 5 is utilized, the ends 5a thereof being passed through the cover and bent inwardly 45 to clamp the cover to the plate, as indicated in Fig. 5. The projections or ears 1b are replaced by the ring holder 6 of the form shown in Fig. 6. This comprises a metal strip or clip which is crimped inwardly near its ends 50 as shown at 6a after its projecting parts 6b have been passed through the cover and thus serve to secure the ring holder in position, as well as to clamp the cover to the back plate. The perforated projections 6b are then bent 55 at a suitable angle to receive and support the rings 2 in the same way as described with reference to Figs. 1 to 4.

It is apparent that this invention is simple in its form of structure and may be economically manufactured and readily assembled,

as well as being conveniently and easily made to suit any particular requirements. Although preferred embodiments of this invention have been shown and described, modifications may be made without departing from the scope of the invention.

I claim:

1. A loose leaf binder comprising a main element having inwardly projecting oppositely located perforated projections, and inwardly extending clamping projections, rings passing through the perforations, and a cover clamped to said main element by said clamping projections.

2. A loose leaf cover comprising a back plate, perforated oppositely located ring supports extending inwardly at an angle from said back plate, and rings carried by said supports.

3. A loose leaf cover comprising a back plate, perforated oppositely located ring supports extending inwardly at an angle from said back plate, rings carried by said supports, a cover located against the inner surface of said plate, and inwardly extending clips for holding said cover against said plate.

4. A loose leaf binder comprising a back plate having a series of projecting lips and oppositely disposed inwardly extending perforated ears, a cover clamped between said lips and said plate, and rings supported by said ears and passing through the perforations thereof.

5. A loose leaf binder comprising a back plate, a cover having its back portion located against the inner side of said plate, a plurality of clips extending around the outside of said plate and clamping the cover against the inside of said plate and having oppositely disposed inwardly inclined perforated projections, and a plurality of rings carried by said projections and passing through the perforations thereof.

6. A loose leaf binder comprising a back plate, a cover having its back portion located against the inner side of said plate, and a plurality of clips extending around the outside of said plate and having inwardly extending projections for clamping said cover against the inside of said plate.

GEORGE LOCKE CROSBY.
